(57) **CLAIM**

The ornamental design for a delivery robot, as shown and described.

DESCRIPTION

1. Delivery robot

1.1 : Top, front, right-side perspective view

1.2 : Bottom, back, left-side perspective view

1.3 : Front

1.4 : Back

1.5 : Left

1.6 : Top

1.7 : Bottom

1.8 : Reference view

The broken lines shown in reproductions 1.1 to 1.7 depict portions of the delivery robot that form no part of the claimed design; a right view is omitted because it is a mirror image of the left view; reproduction 1.8 illustratively shows a state of use wherein the broken lines depict environmental structure that form no part of the claimed design.

1 Claim, 8 Drawing Sheets
